UNITED STATES PATENT OFFICE.

MELVIN L. SEVERY, OF ARLINGTON HEIGHTS, MASSACHUSETTS.

SYNTHETIC HARMONOGRAm-PRODUCER.

1,201,513.

Specification of Letters Patent. Patented Oct. 17, 1916.

Application filed February 25, 1910. Serial No. 545,985.

To all whom it may concern:

Be it known that I, MELVIN L. SEVERY, a citizen of the United States, residing at Arlington Heights, in the county of Middlesex and Commonwealth of Massachusetts, have invented certain new and useful Improvements in Synthetic Harmonogram-Producers, of which the following is a specification.

10 The object of this invention is the construction of means for synthetically producing and graphically recording the resultants of sound waves of various pitches and timbres; means for the reproduction 15 thereof in audible tones being set forth and claimed in my co-pending application Serial No. 756,169.

This mechanism is not designed for the production of graphic representations of 20 sound waves through devices operated by the sound waves themselves, but for the mechanical production of the graphic representations of simple and complex sounds. In other words, the invention is for the purpose 25 of devising a machine which will inscribe a resultant line graphically representing a given sound, the machine comprising a plurality of moving members acting together for such purpose, and said members being made adjustable in their actions 30 in order to form any desired variety of resultant lines.

To this end, I have herein set forth two 35 main types of the harmonogram producer embodying my invention, one thereof being entirely mechanical, and the other fluo-mechanical.

Referring to the drawings forming part 40 of this specification, Figure 1 is a plan view of my mechanical harmonogram producer. Fig. 2 is a side elevation, partly in section, of my fluo-mechanical form of the same. Fig. 3 is a plan view of the inscriber portion of my device showing the same arranged 45 for inscribing a resultant upon a thin disk. Fig. 4 is an illustrative view of a reproducer which can be employed for the audible reproduction of tones from the synthetically constructed form-waves. Fig. 5 50 is a view of another means for converting the rotary motion of the drive shaft into reciprocation required for the plungers of

the fluo-mechanical harmonogram producer. Fig. 6 is still another form of such means.

Examining Fig. 1 first, the reference 55 numeral 1 designates a shaft uniformly rotated by any suitable means, as power belted to the drive wheel 2, and having mounted thereon a plurality of worms 3, 3^a, 3^b, 3^c, etc. Although four such worms are illustrated, 60 the number may be considerably increased, and, in fact, the machines would usually have many more.

The worms 3^a, 3^b and 3^c are slidably carried by said shaft, a spline and groove 4 65 causing them to turn with the shaft. Surrounding each of the last named worms is a light frame 5 supported on suitable ways 6, and transversely mounted in each of said frames is a shaft 7 having a face plate 8 70 at each end thereof. On each face plate is a pin or screw 9 from which a pitman 10 extends to a shaft 7, beginning with the face plates connected with the left hand shaft, and the last pitman uniting and carrying 75 a marker or graver 11 bearing upon the surface of a uniformly rotated drum 12. Said drum 12 is mounted on a shaft separate from, but preferably geared to, the shaft 1, in order that it shall rotate at a speed bearing a definite ratio to, but preferably slower than, the speed of said shaft 1. Such a 80 gearing is illustrated in Fig. 2 for the drum 28. Usually the drum 12 does not require to make more than a single complete revolution 85 for the desired inscription of the resultant line 14, while during the same time the shaft 1 has made many revolutions; after which the paper carrying the harmonogram 14 thus produced, may be removed 90 from the drum 12, and another paper applied thereto.

On each shaft 7 is a worm gear 13 meshing with the worm above it and rotated thereby. Hence the resultant to be inscribed by the marker or graver 11 on the paper, wax or metal surface of the drum 12, will be a zig zag line 14 embodying a representation of the total of all the throws of the pins or screws 9, some advancing while others are retreating, some remaining stationary as regards throw, and some short and others long in throw.

To accurately represent the resultant of

a complex musical note, the pitches of the worms 3, 3^a, 3^b and 3^c should be so arranged that the second shaft 7 rotates twice as fast as the first shaft; the third shaft, three times as fast as the first; the fourth, four times as fast and so on. The curve given by the first shaft's pitman on the drum would therefore represent the fundamental of a certain musical note. The second shaft's pitman would add a first harmonic to the curve; the third, a second harmonic, and so on.

By varying the throws of the pins or screws 9, the relative dominance of the various harmonics can be changed as desired; and by locating any such pair of screws or pins at the axial center of their shaft, their throw will be made zero, and the harmonic represented thereby will be eliminated from the resultant. The face plates being held by set screws 32 permit change of phase.

In the construction illustrated by Fig. 2, there are shown four shafts 15 but which number can be indefinitely extended, each having a face plate 16 from which runs a pitman 17 to a plunger rod 18. Each said plunger rod carries a piston 19 at its lower end fitting within a cylinder 20; such cylinders being connected to a larger cylinder 21, as by the pipe 22. In the cylinder 21 is a plunger 23 from which rises a rod 24 joined by a link or links 25 to an elbow or elbows 26 carrying markers or gravers 27; the latter being adapted to mark or engrave a suitably prepared surface on the drum 28. Said cylinders being provided with a suitable fluid, the effects of any movements communicated to the plunger rods 18 will be immediately communicated to the plunger rod 24, and thence in that proportion graphically imparted to the drum.

The speeds of the shafts 15 being made relatively one, two, three, four, etc., as by the sprocket chains and sprocket wheels 30, 31, the first piston will represent the fundamental; the second, the first harmonic; the third, the second harmonic, etc., of any musical note. By varying the throws of the different pitmen, the effects of the harmonics can be correspondingly altered on the drum; and by angularly changing the face plates on their shafts, and consequently the phase of the harmonics, as by the set screws 32, other changes in the resultant curves can be readily secured.

In Fig. 2 the face plates or disks 16 are represented as radially slotted, and the several crank-pins or studs are represented as passing through such slots. Usual means of securing the pins at any adjustment being provided, it will be seen that they may be placed at any point in the length of the slots, thus permitting adjustment by in-

finitesimal increments, and enabling the user to secure a nicety or perfection of adjustment and a variation of effect which would be impossible through a step-by-step adjustment, that is, through an adjustment from one predetermined point to another predetermined point in fixed relation to the first. The ability so to adjust the crank-pins and the consequent stroke of the plungers or displacement members enables the user not only to compensate for inaccuracies in location of fixed points of adjustment, but permits also of so shading or varying the adjustment as to get effects intermediate those incident to step-by-step adjustment.

By wrapping the drum 28 with a ribbon of sheet iron or other magnetically attractive substance; inscribing thereon as above set forth a double resultant timbre-curve, and then cutting away the metal outside such curves, such embodied resultant can be placed upon the reproducer illustrated by Fig. 4, and the nature thereof made audibly evident. Such ribbons may be made by a great variety of methods all adaptable to this device.

The form of reproducer illustrated in Fig. 4 consists of a uniformly rotated drum 35, an open magnetic circuit electromagnet 36, a source of current 37 in circuit with one arm of said electromagnet, and a telephone receiver 38 in circuit with the other arm of said electromagnet. The poles of this electromagnet are, as shown in the drawing, arranged far enough apart to permit the widest sections of the iron harmonogram 39 to freely pass between them. As said drum 35 revolves, and the harmonogram passes between the poles of the electromagnet, the changes in magnetic flux thereby caused are delivered to the telephone receiver 38 and by the latter rendered audibly evident. Instead of thus inscribing the harmonogram upon the face of a drum, it may be traced upon the lateral face of a thin disk, and then such disk shaped thereto for use in a reproducer of the type set forth in my companion application. A disk being thus inscribed is shown in Fig. 3, where 40 designates the disk having an inscriber 27 contacting therewith.

In order to so adjust the liquid contents of the harmonogram producer shown in Fig. 2 that the inscriber shall be at the proper point when the main piston is at zero, I provide an auxiliary cylinder 41 having a forcibly adjustable piston 42 therein; such adjustment being preferably by having the piston rod threaded and turning in a correspondingly threaded cap 43 held by the cylinder.

Although I have shown cranks and pitmen in Figs. 1 and 2 as a means for converting the rotary motion of certain members into reciprocation of the pistons and marker,

I do not restrict myself thereto, inasmuch as cams 45 may be substituted therefor, as shown in Fig. 5, or a rod-head 46 with a transverse slot 47 may be used in place of 5 the pitman, as shown in Fig. 6. In some ways, the cam and transverse slot 47 are preferable to a pitman, because of the nearer approach to a sine wave which may be given by them.

10 In the device shown in Fig. 2, I have illustrated pistons moved by plunger rods, and have shown the fluids in the cylinders at a variety of heights, but I do not confine myself to this construction of my fluo-mechanical wave-writer. It is obvious that the 15 pistons of Fig. 2 might be replaced by loosely fitting displacement plugs 19', and the whole system operated by displacement changes of the level of the fluid in the cylinders, and in many cases I should prefer this 20 construction. See Fig. 6.

Furthermore, I wish it understood that the sizes and proportions shown may be varied at will without in the least departing 25 from the spirit of the invention. In some cases, I prefer to make the tubes or cylinders representing the various harmonics smaller as the number of the harmonic rises; for the reason that usually the higher 30 harmonics are fainter than the lower ones, and this plan would call for less radical adjustment elsewhere. The displacement principle, while it necessitates slower action, avoids all difficulty of piston leakage and 35 friction.

In the drawings, the inscriber or tracing point moves with the resultant motion and the surface, upon which the record is made, also, moves. It is obvious that all that is 40 needed is correct relative motion between inscriber and recording surface, and all of these motions might be given to the inscriber without departing from the spirit of my invention. I prefer, however, to move 45 the inscriber in accordance with the harmonic resultants, and to move the recording surface as I have shown in the drawings.

It should be remembered that the mechanisms illustrated by Figs. 1 and 2 are not 50 for the production of music directly, or for the production of wave-lines from musical tones, but they are for the purpose of enabling such wave-lines to be inscribed through wholly mechanical or fluo-mechanical means, the wave-lines or harmonograms 55 serving as graphic illustrations of complex musical tones, or as a basis for a later reproduction of actual musical tones.

What I claim as my invention and for 60 which I desire Letters Patent is as follows, to wit:—

1. A harmonogram producer, comprising a movable element; inscribing means controlled thereby; steadily-moved means hav-

ing a surface acted upon by said inscribing 65 means; any desired number of different instrumentalities conjointly affecting said movable element; and adjusting means for each of said instrumentalities, capable of affording infinitesimal variations in the position and consequent effect of each, in contradistinction to a step-by-step adjustment.

2. A harmonogram producer, comprising a steadily moving support for a body to be inscribed; a fluid-container; a fluid therein; 75 an inscribing device; a plurality of different but operatively connected instrumentalities acting upon the fluid in said container and serving by their conjoint action thereon to move and position the inscribing device relatively to the moving support; and connections between the several parts whereby they are positively driven in proper timed relation.

3. A harmonogram producer, comprising 85 a steadily moving support for a body to be inscribed; a fluid-container; a fluid therein; an inscribing device; a plurality of different but operatively connected instrumentalities acting in different but predetermined degrees upon the fluid in said container and serving by their conjoint action thereon to move and position the inscribing device relatively to the moving support; and connections between the several parts whereby they 90 are positively driven in proper timed relation.

4. A harmonogram producer, comprising a fluid-container; a fluid therein; inscribing means subject to and movable by pressure of 100 said fluid; a steadily moving support for a surface to be inscribed; a plurality of separate pressure devices operatively connected to move at different but predetermined rates and each acting upon the fluid; and driving 105 connections between the several parts, serving to move them in proper timed relation, whereby the inscriber is caused to move relatively to the moving support and to the body to be inscribed, in accordance with the combined action of the pressure devices.

5. A harmonogram producer comprising a plurality of cylinders communicating with each other, pistons fitted to the same, an inscriber connected with one of the pistons, 115 and means for simultaneously moving some of the other pistons in some predetermined manner.

6. A harmonogram producer comprising a plurality of cylinders communicating with each other, pistons fitted to the same, an inscriber connected with one of the pistons, a moving surface in contact with said inscriber, and means for reciprocating the said other pistons at speeds bearing the relationship of one, two, three, four, etc. times per 120 unit of time.

7. A harmonogram producer comprising

a plurality of cylinders communicating with each other, pistons fitted to the same, an inscriber connected with one of said pistons, a moving surface in contact with said inscriber, and harmonically rotated displacement members reciprocating said pistons.

8. A harmonogram producer comprising a plurality of cylinders communicating with each other, pistons fitted to the same, an inscriber connected with one of said pistons, a second of said pistons being forcibly adjustable, means for simultaneously reciprocating the other pistons, and a moving surface contacting with said inscriber.

15. 9. In a harmonogram producer, the combination of a reciprocating member, a pair of pivoted bell-crank levers having inscribing means at an end of each, connections between said member and levers, and a moving surface in contact with said inscribing means.

20. 10. A harmonogram producer comprising, in combination, a uniformly moving surface; a pair of inscribers for marking said surface; a plurality of movable elements;

means for moving said elements simultaneously but unequally; and means interposed between said movable elements and the inscribers, whereby the latter are given reciprocating movements which are the resultant of the movements of the several movable elements.

25. 11. A harmonogram producer comprising, in combination, a plurality of movable members; means for positively moving said members, each at a definite rate different from that of the others; a recording device comprising a moving record-receiving surface and an inscriber; and a fluid medium interposed between the movable members and the inscriber, and serving to impart to the latter the resultant of the movements of the several moving members.

30. 35. In testimony that I claim the foregoing invention, I have hereunto set my hand this 27th day of January, 1910.

40. MELVIN L. SEVERY.
